UNITED STATES PATENT OFFICE.

SYDNEY CROSBIE, OF NEW BARNET, ENGLAND.

APPARATUS FOR VAPORIZING OIL.

1,120,450.

Specification of Letters Patent.

Patented Dec. 8, 1914.

Application filed August 1, 1913. Serial No. 782,434.

To all whom it may concern:

Be it known that I, SYDNEY CROSBIE, a subject of the King of Great Britain, residing in New Barnet, England, (whose post-office address is The Chestnuts, New Barnet, in the county of Herts, England,) have invented certain new and useful Improvements in or Connected with Apparatus for Vaporizing Oil, of which the following is a specification.

This invention relates to apparatus used in conjunction with oil fuel furnaces, for the atomizing and vaporization of the fuel simultaneously with its mixture with air which apparatus is of the kind wherein the liquid fuel is atomized by means of a revolving atomizing device and an intimate mixture of the air and oil, in any desired proportions, is obtained prior to its injection into a furnace for complete combustion therein.

It consists in improvements according to which the devices for effecting the mechanical atomizing simultaneously with the carbureting and vaporizing of the oil and for providing the feed of oil and for supplying the air to the atomizing device are operatively connected and driven from a single source of power, while means are provided for varying the height of the longitudinal axis of the apparatus, for altering the direction of the vaporized oil issuing from the delivering end of the apparatus and for periodically rotating the carbureting tubes employed.

The improved apparatus may be mounted on wheels to be of a portable nature.

The invention will be described with reference to the accompanying diagrammatic drawings, in which—

Figure 1 is a side elevation of an apparatus constructed according to this invention; Fig. 2 is an elevation of the reverse side of the apparatus; Fig. 3 is a furnace end view of the apparatus; Fig. 4 is the front view of the apparatus; Fig. 5 is a partial section through A—B marked on Figs. 1 and 2; Fig. 6 shows a part of the apparatus in section through C—D on Fig. 3; and Fig. 7 is a sectional detail of a conical atomizing device.

An oil vaporizing apparatus constructed according to my invention comprises a chamber E of suitable shape and of cast iron, wrought iron, mild steel, or other suitable metal. Within the chamber is ar-

ranged one or more pipes H for a purpose hereinafter referred to. This chamber is lined within by fire bricks, ganister, mixtures of magnesium lime stone and carbon, or other refractory substances, to prevent the radiation of heat and incidentally the gradual oxidation of the metal case. The chamber may be further protected on the exterior by a layer of non-conducting material such as infusorial earth, slag wool, or other good non-conducting materials, covered in and held in position by sheets of charcoal iron, the object of which is also to prevent radiation of heat.

Upon the front end of the apparatus is bolted an air box I of suitable form. To the bottom of this air box is attached an iris diaphragm air regulator which directs the incoming air always axially, that is to say centrally; to this iris diaphragm is attached outside the air box a worm wheel Z adapted to be actuated by a worm upon a shaft z to which mechanical movement is communicated from the shaft of an oil inlet regulator to be subsequently described. The pipe upon which this worm wheel is fixed has upon it a bellows O fitted with a slipping fit so that the worm wheel may be revolved without revolving the bellows below it, the bellows is made of leather or other suitable material, and is connected to the fan M for providing the air required for combustion.

Passing from the air box through the chamber E, which may be of any suitable shape for instance circular as shown, are the two pipes H into which the air is blown by fan M. The pipes H are attached to the ends of chamber E in glands e in such a manner that they may be rotated in those ends, ball bearings being provided if necessary. Into each of these pipes H is passed a small pipe S for conveying the oil to be atomized and upon the ends of these small pipes and within the larger pipes H are cones S' furnished upon their extreme faces or ends with sharp cutting edges as shown in Fig. 7. Alternatively these cones may be similar to those described in my British specification No. 18917 of 1912 and in my co-pending United States patent application Serial No. 758515 filed April 29, 1913.

The cone carrying pipes S pass through the outer wall of the air box I to its exterior and enter chambers R which serve as stuffing boxes.

At right angles to the pipes S is a

shaft *g* carried by bearings constituted by tubular members which pass through chambers *R* and are supported by the walls thereof. To each of the cone carrying pipes *S* is keyed a toothed bevel wheel *d* which meshes with a similar bevel wheel *f* upon the shaft *g*.

The oil is passed into the chambers *R* by flexible tubes *i*, the oil being aspirated by pumps *Q* through oil regulators *P* and forced into the chambers, thence through the pipes *S* which are adapted to be turned upon ball bearings at high speed.

By reason of the high speed at which 15 these pipes turn, the oil when it reaches the edge of a cone is cut to pieces and thrown out into the larger pipe *H* where it is mixed with the air therein and becomes in physical appearance like a white fog and, assisted by 20 the heat from the flame of a burner *N* arranged so that the flames may be projected into the chamber *E*, is vaporized. The burner flame may be regulated by any suitable means.

25 The flame acting on the exterior of the two pipes in which the cones are revolving causes the vaporization of the oil, while the carbon monoxid and other gases are projected with a whirling motion into the furnace where they take up sufficient oxygen to produce complete combustion of the fuel.

The large chamber *E* is provided with short chimneys *F¹*, *F²* to allow the surplus heat to pass off and to provide a current 30 of air for the burner.

The oil and air regulator, which is the subject of my British specification No. 25410 of 1911 and is fully described therein is preferably used in apparatus constructed according to the present invention, for the purpose of delivering the oil and air through the respective devices in such a way that the turning of the handle upon the oil regulator fitted with suitable transmission gear will cause the delivery to the pipes *H* in the chamber *E*, constituting a carbureter, the proper proportion of air that is required to combine with the oil, and the gears may be changed according to whether 45 it is desired to produce a reducing flame or an oxidizing flame in the furnace, and may be of any ratio.

The chamber *E* and the associated parts are carried by a frame or carriage *K* provided with wheels *L*, *L* of any convenient size. On the frame *K* are bearings *J* which can be adjusted as to height by means of the screw device *J'*, so that the height of the axis of the chamber *E* can be varied. 55 At the furnace end of the frame is arranged a suitable screw raising or lowering device *U* which can be operated to lift or lower the furnace end of chamber *E* turning about the bearing *J*. By operating the device *J'*, 60 the chamber *E* and associated parts may be

bodily raised or lowered, and by working device *U* the discharge end of the chamber may be brought into registration with the part of the furnace with which it is to co-operate.

The pivoting or tilting features of the apparatus are very useful, for the reason that they permit the combined gases to be injected into a furnace or combustion chamber, with which the apparatus is to co-operate, at any desired height, and either downward upon any metal under treatment, or upward in the case of furnaces of a certain construction.

The mechanism of my apparatus may be driven in any suitable manner as for instance by electricity as illustrated in the drawings, but in any case, whatever the motor, the air fan only is driven by it, the power required for the other parts of the mechanism being taken from the extended shaft *m* of the fan. Off this shaft is carried a chain or belt *n* to a wheel *V* on the shaft *g*. The fan *M* and the prime mover, such as motor *a*, may be mounted on a separate carriage *M'* connected or coupled in suitable manner to the frame *K*. Upon shaft *g* are keyed wheels *W* connected by belts or chains to gears *X* on counter-shafts operatively connected to wheels *Y* which in turn communicate their motion to the pumps *Q* aspirating the oil through the oil regulators *P* and delivering it under pressure to the stuffing boxes *R*.

The pipes *H* passing through the chamber *E* and in which the oil is atomized as it leaves the cones, have each fixed upon them, by set pins or keys, a worm wheel *T* actuated by a worm *T'* on a shaft *T''* which is turned by a capstan wheel *T'''*. By these means the pipes may be periodically turned through any desired angle, the object of this being to present a new surface to the heat in order to give the pipes a longer life than what they would have if the necessary heat were allowed to impinge on the same surface of the pipe always; the burning through of the pipes is thus delayed.

In the furnace associated with the apparatus of this invention the atomized mixture is completely burnt to CO_2 which passes out of the uptake into the atmosphere.

For firing boilers on board ships, the apparatus may be carried upon either low 120 wheels or the wheels may be omitted in order to accommodate itself to the openings of the fire boxes in marine boilers. In such cases the chamber *E* is preferably made smaller in diameter and contains only one 125 vaporizer or atomizing tube. For marine purposes it is not necessary for the fans to be attached to the frame of the apparatus for they may be placed in any convenient position.

The worm wheel Z for operating the iris diaphragm air regulator is actuated by means of a worm on shaft z, which is driven by means of the driving connections g, Fig. 2, from the shaft of one of the oil regulators P whereby a simultaneous regulation of oil and air feed is effected as described in my specification No. 25410 of 1911. This regulator is geared so as to open the diaphragm sufficiently to provide air in the proper proportion for the two pipes H. The regulator which is not so connected up is adjusted to the same index on the dial as that of the regulator connected up.

Having thus described the nature of the said invention and the best means I know of carrying the same into practical effect, I claim:—

1. In oil vaporizing apparatus of the character referred to, and provided with a carbureting tube, a rotatable oil atomizing device within the carbureting tube, a device operating to effect the feed of oil to the atomizing device, a device for supplying air centrally to the carbureting tube, driving gear operatively connecting said three devices and adapted to be driven from a single source of power, and means for heating the carbureting tube whereby the vaporization of the atomized oil is effected.

2. In oil vaporizing apparatus of the character referred to and provided with a carbureting tube, devices operating to effect respectively the feed of oil and air to the carbureting tube, driving gear operatively connecting said devices and adapted to be driven from a single source of power, and means for varying the height of the longitudinal axis of the body of the apparatus.

3. In oil vaporizing apparatus of the character referred to and provided with a carbureting tube, devices operating to effect respectively the feed of oil and air to the carbureting tube, driving gear operatively connecting said devices and adapted to be driven from a single source of power, means for varying the height of the longitudinal axis of the body of the apparatus, and means for varying the inclination of said axis whereby the direction of the vaporized oil issuing from the delivery end of the apparatus may be altered.

4. In oil vaporizing apparatus which is of the character referred to and has a carbureting tube, a rotatable oil atomizing device within the carbureting tube, a device operating to effect the feed of oil to the atomizing device, a device for supplying air to the carbureting tube, driving gear operatively connecting said three devices and adapted to be driven from a single source of power, and means operating to rotate the carbureting tube for the purpose described.

5. In oil vaporizing apparatus which is of the character referred to and has a plu-

rality of carbureting tubes, a rotatable oil atomizing device within each carbureting tube, a device operating to effect respectively the feed of oil to the atomizing devices, a device for supplying air to the carbureting tubes, driving gear operatively connecting all said devices and adapted to be driven from a single source of power, and means adapted to rotate the said tubes for the purpose described.

6. In oil vaporizing apparatus which is of the character referred to and has a carbureting tube, devices operating to effect respectively the feed of oil and air to the carbureting tube, driving gear operatively connecting said devices and adapted to be driven from a single source of power, means for varying the height of the longitudinal axis of the body of the apparatus, and means operating to rotate the carbureting tube for the purpose described.

7. In oil vaporizing apparatus which is of the character referred to and has a carbureting tube, devices operating to effect respectively the feed of oil and air to the carbureting tube, driving gear operatively connecting said devices and adapted to be driven from a single source of power, means for varying the height of the longitudinal axis of the body of the apparatus, means for varying the inclination of said axis whereby the direction of vaporized oil issuing from the delivery end of the apparatus may be altered, and means operating to rotate the carbureting tube for the purpose described.

8. Oil vaporizing apparatus of the character referred to comprising a portable wheeled frame, a chamber mounted on said frame, means for heating said chamber, a plurality of carbureting tubes within the chamber, devices operatively connected and driven from a single source of power and adapted to effect respectively the feed of oil and air to the carbureting tubes, means driven from the same source of power for atomizing the oil fed to the tubes, means operatively connecting the oil and air feed devices and adapted to control the air feed device to deliver air in suitable proportion to the oil feed, means for varying the height of the longitudinal axis of the chamber, and means for varying the inclination of said axis whereby the direction of the vaporized oil issuing from the delivery ends of the tubes may be altered.

9. Oil vaporizing apparatus of the character referred to, comprising a portable wheeled frame, a chamber mounted on said frame, means for heating said chamber, a plurality of carbureting tubes within the chamber, devices operatively connected and driven from a single source of power and adapted to effect respectively the feed of oil and air to the carbureting tube, means

driven from the same source of power for atomizing the oil fed to the tubes, means operatively connecting the oil and air feed devices and adapted to control the air feed device to deliver air in suitable proportion to the oil feed, means for varying the height of the longitudinal axis of the chamber, means for varying the inclination of said axis whereby the direction of the vaporized oil issuing from the delivery ends of

the tubes may be altered, and means for rotating said carbureting tubes for the purpose described.

In testimony whereof I have signed my name to this specification in the presence of 15 two subscribing witnesses.

SYDNEY CROSBIE.
